BOOK COVER

Isadore Lawrence Lesavoy, Allentown, Pa.

Application November 10, 1945, Serial No. 627,887

6 Claims. (Cl. 224—47)

1

This invention relates to new and useful improvements in book covers and carriers.

The object of the invention is to provide a simple and efficient device which is made of one piece of material folded and cut in a novel manner to act as a book cover and carrier.

Briefly and generally speaking the invention, in its preferred form, includes a single sheet of material of paper, cloth, or leather. This sheet is folded along its top and bottom edge in the usual manner to provide means to enclose the top and bottom portions of covers of a book. The end portions of the sheet are folded over toward each other in the usual manner to enclose the front portions of covers of a book.

Outwardly beyond the line of fold the end portions are cut in two spaced lines, each line beginning and ending at the line of fold, and this cutting forms a handle portion and, in the preferred form, a flap portion which is adapted to act as a book mark. Preferably the lines of cutting are parallel and arcuate in formation; and in a modified form of my invention the handle portions and the area of the sheet immediately adjacent the line of fold are reinforced to provide extra strength when the sheet is adapted to act as a book carrier.

The present preferred forms which the invention may assume is illustrated in the drawing, in which,

Fig. 1 is a perspective view of the device of my invention partially folded into position.

Fig. 2 is a perspective view of the device folded ready to receive a book cover;

Fig. 3 shows a perspective view of the device with a book enclosed therein and adapted to be supported thereby; and

Fig. 4 shows a fragmentary perspective view of a modification of my invention.

As shown in the drawing, the present preferred form of the device includes a sheet of material 10 which along its top and bottom edges 9 is folded inwardly to form lateral flaps 11. The sheet at its ends is then folded transversely along the lines 12 to form front flaps 16, and these portions in the usual manner are adapted to receive and partly envelop the covers of a book.

Outwardly beyond each transverse fold 12 the sheet is cut along spaced lines 7 and 8 to form an aperture 6, a handle portion 13 and a medial flap 14 which is preferably employed as a book mark. As shown in Fig. 3 the flaps 16 are bent to envelop the covers of a book which is placed in the usual manner on the sheet. The handle portions 13 are then extended upwardly as shown 55

2

to be gripped in the hand so that the device may act as a book carrier as well as a book cover. The medial flaps 14 extending as shown may be employed to retain the marking of one or two places in the book.

This device is simple and inexpensive, since it can be made from one piece of material which may be paper, leather, cloth or other similar material. If it is desired to reinforce the device, 10 I cover the handle portions 13 and the area of the sheet just inside the transverse folds 12 with an extra reinforcing layer 15 so that these portions, which are subjected to most of the wear and tear and strain will be strengthened.

15 Although the lines 7 and 8 along which the handle and flaps are cut are illustrated as being parallel and semicircular, they may be made non-parallel and of other shapes than circular or arcuate. However the cutting lines 7 and 8 preferably, although not necessarily, intersect the transverse folds 12.

While the invention has been described in detail and with respect to a present preferred form thereof, it is not to be limited to such details 25 and form since many changes and modifications may be made in the invention without departing from the spirit and scope of the invention in its broadest aspects. Hence it is desired to cover any and all forms and modifications of the invention which may come within the language or scope of any one or more of the appended claims.

I claim:

1. A book cover and carrier comprising a sheet 35 of material folded inwardly adjacent its ends along transverse lines to form cover flaps, and a handle cut from at least one of said flaps and integral with the sheet, said handle extending outwardly in the direction opposite the inward folding of the cut flap.

2. A book cover and carrier comprising a sheet 45 of material folded inwardly adjacent its ends along transverse lines to form cover flaps, a substantially arcuate apertured portion in at least one of said flaps, and a handle formed from said apertured portion and integral with the sheet, said handle extending outwardly in the direction opposite the inward folding of the apertured flap.

3. A book cover and carrier comprising a sheet 55 of material folded inwardly adjacent its ends along transverse lines to form cover flaps, a substantially arcuate apertured portion in at least one of said flaps, and a handle and a medial flap formed from said apertured portion and integral

with the sheet, said handle extending outwardly in the direction opposite the inward folding of the apertured flap and said medial flap being foldable inwardly to serve as a book mark.

4. A book cover and carrier which comprises a sheet of material folded inwardly adjacent its ends along transverse lines of fold, and cut outwardly beyond the lines of fold along two spaced lines to form a handle portion, said handle portion extending outwardly in the direction opposite the said inward folding of the sheet, and a flap portion adapted to be folded inwardly to act as a book mark.

5. A book cover and carrier which comprises a sheet of material folded adjacent its ends along

15

transverse lines of fold to enclose the covers of a book, and cut outwardly beyond the lines of fold along two spaced arcuate lines to form a handle portion, said spaced lines intersecting the line of fold.

6. A book cover and carrier which comprises a sheet of material folded adjacent its ends along transverse lines of fold to enclose the covers of a book, and cut outwardly beyond the lines of fold along two spaced parallel arcuate lines to form an arcuate handle portion and a medially disposed flap portion adapted to act as a book mark.
